UNITED STATES PATENT OFFICE

CLYDE C. FARMER, OF PITTSBURGH, AND THOMAS H. THOMAS, OF EDGEWOOD, PENNSYLVANIA, ASSIGNORS TO THE WESTINGHOUSE AIR BRAKE COMPANY, OF WILMINGTON, PENNSYLVANIA, A CORPORATION OF PENNSYLVANIA

ELECTRIC SIGNAL SYSTEM

Application filed March 25, 1927. Serial No. 178,305.

This invention relates to signal systems, and more particularly to an electric signalling system adapted for use on railway trains.

5 The principal object of our invention is to provide an electric signal system employing only a single train wire and in which a source of current is not required on the locomotive or head car

10 In the accompanying drawing; Fig. 1 is a diagrammatic view of an electric signal system embodying our invention; Fig. 2 a section on the line 2-2 of Fig. 1; and Fig. 3 a section on the line 3-3 of Fig. 1.

15 According to a preferred form of our invention, there is provided on each car of the train a buzzer device comprising an electro-magnet 1 having two magnet windings or coils 2 and 3 and a pivoted armature 4, movable in one direction by a spring 5, when the magnet is deenergized and in the opposite direction when the magnet is energized. One terminal of each coil 2 and 3 is connected to a single train wire 6, and the other terminal of coil 2 is connected to a wire 7 which leads to a contact 8 controlled by a plug switch device comprising a casing 9 having a tapered bore adapted to receive a removable switch plug 10. The switch plug 10 carries 20 contacts 11 and 12.

A branch wire 13 leads from wire 7 and has a terminal contact 14 controlled by a switch device comprising a casing 15 containing a sliding contact member 16. Said contact member 16 is provided with an operating stem 17 adapted to be operated by a lever 18 having two operating arms 19 and 20, each adapted to be connected to an operating cord and having two fulcrum pins 21 and 22, so disposed that when the arm 20 is operated, the lever 18 turns about the fulcrum pin 22 to operate the stem 17 and when the arm 19 is operated, the lever 18 turns about the pin 21 to operate the stem 17.

45 The contact member 16 is provided with contacts 23 and 24 and is normally maintained in the position shown in the drawing by the action of a coil spring 25. When the member 16 is moved downwardly a predetermined distance, a yielding stop member

26 is engaged, said stop member being subject to the pressure of a coil spring 27. In order to prevent rotative movement of the contact member 16, said member is provided with a spline 28 which engages in a groove cut in guide bushing 29 having screw-threaded engagement in the casing 15. The switch plug 10 may also be provided with a spline 30 adapted to engage in a groove in the casing 9, so as to ensure that the plug will be inserted in the proper position. 55 60

The contact 24 controls circuit wires connected to the contact 14, to contact 31 which is connected to wire 32 leading to one terminal of magnet coil 3, and to contact 33 which is connected to wire 34 leading to the position terminal of a battery 35, or other source of electric current. 65

The contact 23 controls circuit wires connected to contacts 36 and 37, the contact 36 being connected to a wire 38, leading to the negative terminal of the battery 35, and the contact 37 being connected to a wire 39 which is connected to ground at 40 and which also leads to a contact 41 controlled by the contact 12 of the switch plug 10.

The wire 34 is also connected to a contact 42 controlled by the contact 11 of the switch plug 10, and the negative terminal of the battery 35 is connected by wire 43 to a contact 44 controlled by contact 12 of the plug switch 10.

On the locomotive, there is provided a switch device comprising a casing 45 in which is slidably mounted a contact member 46 having a contact 47 and normally maintained in the position shown in the drawing by the action of a coil spring 48.

The train wire 6 is connected with two buzzers 49 and 50 in parallel, of the well known type, which operate by making and breaking the electric circuit. The buzzer 49 is connected through wire 51 with a contact 52 and the buzzer 50 through wire 53 with a contact 54. In normal position of the switch member 46, the contact 47 connects contact 52 with a contact 55 having a connection with a wire 56 leading to ground at 57 and when the member 46 is depressed, the contact 47 connects con-

tact 54 with a contact 58, also connected to ground wire 56.

The winding 2 of the electro-magnet 1 is of greater resistance than the winding 3. The buzzers 49 and 50 are connected to the train line 6 in series with the windings 2 and 3, and the buzzer 49 is of such character that it will not respond to current flowing through the winding 2 but will respond to current flowing through the winding 3.

The buzzer 50 is so constructed that it will respond to current flow through either the winding 2 or 3.

There are different ways, well known in the art, for varying the responsiveness of the buzzers 49 and 50, such as, for example, by varying the resistance of the buzzer windings, varying the number of turns of the windings, by varying the magnet air gap between the magnet poles and the armature, or the pull of the usual spring which acts on the magnet armature, or by varying two or more of the above adjustments.

The buzzer 49 on the locomotive and the coil 2 of each electro-magnet 1 on each vehicle of the train are of sufficiently high resistance, so that even if all the plugs 10 on the train are inserted, there will not be enough current flowing through the buzzer 49 to cause same to operate.

In operation, a plug 10 is inserted in the casing 9 by a trainman on each vehicle of the train at which it is desired to receive signals originated by the engineman.

If the engineman desires to signal, he depresses the switch member 46, so that a circuit is closed from the ground 57 through the buzzer 50 to the train wire 6, while the circuit through the buzzer 49 is opened.

On cars in which the plug 10 is inserted, a circuit will then be completed from the train wire 6 through magnet coil 2, wire 7, contact 11 of the plug switch, wire 34, battery 35, wire 43, contact 12 of the switch plug 10, and wire 39 to ground at 40.

The buzzer 50 on the locomotive is thus caused to operate and in operation, it makes and breaks the circuit, so that the circuit of the coil 2 is likewise made and broken and thereby the armature 4 is caused to operate as a buzzer and thus a signal is given on cars in the train in which the plug 10 is inserted.

The buzzer 50 also operates as a signal to the engineman that the apparatus is working properly and that a signal is being made on the cars of the train.

When a trainman desires to signal the engineman, he causes the lever 18 to be operated so as to depress the stem 17, until the contact member 16 engages the stop 26. This completes a circuit from ground 40 to the train wire 6 through contact 23, wire 38, battery 35, wire 34, contact 24, wire 32, and magnet coil 3. On the locomotive, the switch member 46 being in normal position, as shown in the

drawing, the train wire is connected to ground through buzzer 49, wire 51, contact 47, and wire 56 to ground at 57.

The magnet coil 3 is of low resistance as compared with magnet coil 2 and such that sufficient current will flow through the buzzer 49 to cause same to operate and thus signal the engineman. The buzzer 49 being in circuit with the coil 3, will, by its operation, cause the circuit through the coil 3 to be made and broken and thereby the armature 4 will be caused to vibrate.

It will be noted that a trainman may signal the engineman as above described, regardless of whether or not the plug 10 is inserted in the operating position.

If after trainman has signalled the engineman, the trainman wishes the engineman to answer at the point from which he signalled the engineman, the trainman will further depress the switch member 16, so as to move the yielding stop 26 downwardly.

A circuit to the train wire 6 is then completed from the ground 40 through contact 23, wire 38, battery 35, wire 34, contact 24, wire 13, wire 7, and through the magnet coil 2, to the train wire 6. On the locomotive, the circuit is completed through the buzzer 49 and the switch member 46 to the ground, and since the buzzer 49 will not operate with the magnet coil 2 in circuit, and since the circuit of the coil 3 is now open, the armature 4 will cease buzzing when the contact switch member 16 is fully depressed, and thus will indicate to the trainman that he has properly depressed the switch member 16 to permit the engineman to signal back.

If, with the switch member 16 fully depressed, the engineman depresses the switch member 46, a circuit will be completed on the locomotive through the buzzer 50 and through the magnet coil 2 on the car, and the circuit through the coil 2 and the battery 35 being closed in the fully depressed position of the switch member 16, as above described, the operation of the buzzer 50 on the locomotive makes and breaks the circuit through the coil 2 and thus causes the armature 4 to act as a buzzer and as a signal from the engineman to the trainman.

A rectifier 60 or other means for permitting flow of current only in one direction may be interposed in the wire 34, so that should the voltage of the battery 35 on one car be in excess of that on another car, there will be no possibility of a reverse flow of current from the excess voltage car back through the batteries of other cars in which the battery voltage is less.

Having now described our invention, what we claim as new and desire to secure by Letters Patent, is:—

1. In an electric signal system, a train signal circuit, two signal devices at a first station connected in said circuit, a signal de-

vice at a second station having two energizing coils connected in said circuit, one of the signal devices at the first station being responsive to current flow through one coil but not to current flow through the other coil and the other signal device at the first station being responsive to current flow through said other coil, means at the first station for closing the circuit through either one of said signal devices at the first station, and means at the second station for closing the circuit through either one of said coils.

2. In an electric signal system, a train signal circuit, two signal devices at a first station connected in said circuit, a signal device at a second station having two energizing coils connected in said circuit, one of the signal devices at the first station being responsive to current flow through one coil but not to current flow through the other coil and the other signal device at the first station being responsive to current flow through said other coil, a manually operable switch device at the first station for closing the circuit to one of the signal devices at the first station in one position and for closing the circuit to the other signal device at the first station in another position, and a manually operable switch device at the second station for closing the circuit of one coil in one position and for closing the circuit of the other coil in another position.

3. An electric signal system for signaling from one station to another station including a train signal circuit, a signal device at a first station having two energizing coils of different resistances connected in said circuit, means at the first station for energizing either one coil or the other of said coils, two signal devices at a second station connected in said circuit, one of said signal devices at the second station being responsive to current flowing through one coil but not to current flowing through the other coil, and means at the second station for closing the circuit of either one or the other of said signal devices.

4. An electric signal system for signaling from one station to another station including a train signal circuit, a signal device at a first station having two energizing coils connected in said circuit and operative by the making and breaking of the circuit through one of said coils, means at the first station for supplying current through either one or the other of said coils, two automatic circuit make and break devices at a second station connected to said train wire, one of said signal devices at the second station being responsive to current flowing through one coil but not to current flowing through the other coil, and means at the second station for closing the circuit through either one or the other of said automatic circuit make and break devices at the second station.

5. In an electric signal system, the combination with a train signal circuit, of a signal device in said circuit on one car of a train for making a signal by the making and breaking of the circuit and having two energizing coils, one of greater resistance than the other, a manually operated switch for locally closing the circuit through one coil, a manually operated switch for locally closing the circuit through the other coil, two automatic circuit make and break devices in said circuit on another vehicle of the train, so related that one will operate when in series with the high resistance coil and the other will not, and a manually operated switch for locally closing the circuit through either one of said make and break devices.

6. In an electric signal system, the combination with a train signal circuit, of a signal device in said circuit on one car of a train for making a signal by the making and breaking of the circuit and having two energizing coils, one of greater resistance than the other, a manually operated switch for locally closing the circuit through one coil, a manually operated switch for locally closing the circuit through the other coil, two automatic circuit make and break devices in said circuit on another vehicle of the train, so related that one will operate when in series with the high resistance coil and the other will not, and a manually operated switch for locally closing the circuit through either one of said make and break devices and adapted to normally close the circuit through the make and break device which is not responsive to current flowing through the high resistance coil.

In testimony whereof we have hereunto set our hands.
